GIRDLE

Charles Stone, Brooklyn, N.Y.

Application October 28, 1943, Serial No. 507,955

2 Claims. (Cl. 2-38)

This invention relates generally to garments, but more specifically to means for adjusting the girth of the waist portion thereof.

The main object of the invention resides in the provision of means associated with the waist portion of a garment whereby the girth thereof is adjustable, the adjustment not being accompanied by exposed or external bunching or pleating.

A further object of the invention resides in the provision of a garment wherein the said means are simple, economical to apply to the waist region of a garment and which do not result in pleating or bunching at the areas of adjustment.

These objects and other incidental ends and advantages of the invention will hereinafter appear in the progress of the disclosure and as pointed out in the appended claims.

Accompanying this specification is a drawing showing a preferred form of the invention applied to a garment such as a girdle and wherein corresponding reference characters designate corresponding parts throughout the several views, and wherein:

Figure 1 is a front plan view of a garment, such as a girdle, incorporating the invention herein.

Figure 2 is a fragmentary and enlarged fore-shortened view of the front of the waist portion of the garment shown in Figure 1.

Figure 3 is a sectional view of Figure 1 along the plane 3-3 thereof.

In accordance with the invention and the preferred form shown a garment such as a girdle is indicated generally by numeral 10, the said garment having the usual front central panel 11 containing an inverted rubber panel portion 12 at the lower end, auxiliary front lateral panels 13 and 13a, a pair of elastic lateral panels 14. The rear portion of the garment is conventional.

The waist portion of the garment is provided with a pair of lateral flaps 15 and 16 extending from the upper portion of panel 11. Flap 15 is provided with a vertical row of fastening elements such as hooks, each indicated by numeral 17, along the outer vertical edge, the said edge being reinforced by means of an inturned end 18 and a reinforcing strip 19 thereon. Lines of stitching 20 and 21 are adapted to secure the inturned portion 18 and the reinforcing strip 19 together, the lines of stitching 20 and 21 being interrupted at the places where the fastening elements 17 are inserted between the reinforcing strip 19 and the inturned portion 18.

The flap 15 is adapted to project beyond an open edge generally indicated by numeral 22 of

an auxiliary panel portion 23 secured to the upper part of auxiliary panel 13. The means of securement between portion 23 and the auxiliary panel 13 resides in an inwardly inclined line of stitching along adjacent and similarly inclined sides 24 and 25 of portion 23 and panel 13, the said stitching affording a resilient and spaced connection between the members 23 and 13 and being formed in any suitable manner such as by 5 fagoting indicated by numeral 26, or by the use of an equivalent stitch. The auxiliary panel 13 adjacent secured edge 25 has preferably a line of stitching 27 to secure a turned in portion for reinforcing purposes, while portion 23 is provided 10 with a line of stitching 28 for a similar purpose.

Hooks 17 are adapted to engage any one of a plurality of spaced vertical rows of cooperating receiving members disposed on panel portion 23 for purposes of adjusting the girth of the waist portion of the garment. Thus, panel portion 23 is provided with outer horizontally disposed strips 29 and 30 and an intermediate and spaced horizontally disposed strip 31, the said strips being adapted to overlie a plurality of vertically disposed spaced strips 32, 33 and 34. The strips 29, 30 and 31 are secured to panel portion 23 by any means such as lines of stitching 35, 36 and 37 thereby forming from the strips 32, 33 and 34 engaging means for the hooks 17 between the edges of the said horizontally disposed strips as 15 best shown in Figure 2.

The central panel 11 is secured to auxiliary panel 13 in the conventional way as indicated by numerals 38 and 39 there being on the garment 20 shown a placket at the upper portion extending from the inner portion of the lower edge of flap 15 downwardly, the said placket being joined by means of a sliding fastener indicated generally by numeral 40. On the opposing joining edge 25 between central panel 11 and auxiliary panel 13a there is no placket and the same construction exists between a flap 16 and a portion 23' as exists between flap 15 and portion 23.

As shown, panel portion 23 is provided with a lining 41 and an inner edge reinforcing strip 42, said parts at the inner edge being joined by stitching 43. The outer edges of panel 23 and lining 41 are joined by stitching 44.

When the garment is put on the wearer, one or 20 both of the flaps 15 and 16 are secured by means of hooks 17 in the proper receiving members so that the girth fits the wearer. No matter what the adjustment is, the constriction or expansion in the panel portions 23 and/or 23' is compensated by the yieldability of the stitchings 24 and

thereby does not give rise to any external pleating or bunching at these regions. The resiliency afforded by the stitching 24 has both vertical and horizontal components and thereby provides the elimination of such external pleating and bunching in the garment.

I wish it understood that the invention herein is applicable to garments such as skirts or dresses and that minor changes in material, location and integration of parts may all be resorted to without departing from the spirit of the invention and the scope of the appended claims.

I claim:

1. In a girdle, an adjustable waist portion comprising a placket extending downwardly from the upper edge thereof, a placket flap, a panel section adjacent the waist region and having an

open inner edge underlying said placket flap and an inclined lower edge, a main panel, yieldable means of connection between said panel section at the inclined edge and the main panel, and means to adjustably secure the flap and panel section for proper girth fitting.

2. In a girdle, a placket at the waist portion extending downwardly from the upper edge thereof, a placket flap, a panel section adjacent the waist region and having an open inner edge underlying said placket flap, a main panel, a yieldable connecting member to join said panel section at a lower inclined edge to the main panel, and means to secure the flap and panel section for proper girth fitting.

CHARLES STONE.
